BACK REST

Application filed August 11, 1928. Serial No. 298,976.

The invention relates to a portable back rest particularly adapted for use on beaches and lawns, and in camps, and the like.

An object of the invention is to provide a device of the character described which will be strong and relatively light in construction, extremely comfortable when in use, and may be folded together to form a compact, easily transported article.

Another object of the invention is to provide a device of the character described in which the frame members will be formed exclusively of metal of standard material and shape, thereby permitting low cost of manufacture.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by said drawings and description may be adopted within the scope of the invention as set forth in the claim.

Referring to said drawings:

Figure 1 is a perspective view of the rest of our invention operatively disposed.

Figure 2 is a longitudinal sectional view of the rest on a slightly enlarged scale.

Figure 3 is a view similar to Figure 2, but showing the parts folded for carrying or storage.

Figure 4 is a perspective view of a ground gripping attachment which may be used with my device.

The back rest of the invention in its preferred form comprises a pair of frames 5 and 6 formed of strap metal and bent transversely to form a U with the greatest thickness of the metal disposed perpendicular to the general plane of the frame. The frames are pivotally connected together at their open ends by means of a rod 7 the opposite extremities of which extend through and are secured to corresponding side members 8-9 and 10-11 of the frames. The Figure 5 hereinafter termed the back frame since it serves as the back proper of the rest is some-

what shorter and narrower than the frame 6, hereinafter termed the bracing or supporting frame, in order that the former may readily nest within the latter as indicated in Figure 3. Suitable bracing such as the diagonal members 12 and 13 are provided on the supporting frame, and such members are disposed across the remote face of the frame so that the full nesting of the frames will not be interfered with.

Extending across the space between the side members 8 and 10 of the back frame to form a filler therefor is a sheet 14 of flexible material such as canvas or the like, having the sides hemmed to form pockets 16 in which the members 8 and 10 are disposed. An end of the sheet is also hemmed to define a pocket 17 for the reception of the cross rod 7. The sheet is additionally held in position by means of a rod 18 which is secured to the sides 8 and 10 and is positioned adjacent the end 19 of the frame. Attachment of the sheet to the rod 18 is effected by disposal of the latter in a pocket 21 formed in the sheet. It will thus be noted that the sheet is firmly held in position on all sides and that the pressure exerted thereagainst when a person uses the rest is evenly distributed to all portions of the frame.

The attachment between the side members of the two frames is preferably such as to frictionally hold the frame against relative movement, the corresponding sides however being spaced apart sufficiently to permit the ready nesting of the frame 5 within the frame 6 notwithstanding the sheet covering disposed about the side members 8 and 10. One means of obtaining the foregoing is to provide said member with an offset such as clearly shown at 22 of Figure 1.

Preferably formed as an integral portion of the sheet and extending from the portion thereof defining the pocket 21, is an apron 23 which is arranged to serve as a cover or seat on which the person using the rest may sit upon while his back is reclining against the back frame and sheet. It will be noted that the rod 18 is spaced appreciably inward from the end 19 of the frame, and by reason thereof the portion of the apron near the rod

will usually be held taut above the surface on which the rest is positioned when a person is sitting on the apron and reclining against the back, so that a cushion support will be provided for the base of the spine. When the frames are nested for carrying or storage, the apron is preferably placed between the sheet and bracing members 12 and 13 as illustrated in Figure 3.

Under ordinary conditions, the frame members while in use will usually be held against undue spreading by reason of the frictional connection of the frames and the firm engagement of the end 24 of the frame 6 with the supporting surface or the embedding thereof in the ground below such surface. However, should it be desirable that the frame 24 more firmly grip the ground, a gripper 26 such as shown in Figure 4 may be attached to the frame. Preferably the gripper is of angle iron construction, one leg 27 thereof being arranged to be secured to the end 24 by removable screws, while the other leg 28 is formed with teeth to dig into the ground.

It will now be clear that the construction and design of our back-rest is such as to effectively provide for the accomplishment of the objects hereinbefore referred to.

We claim:

A back rest comprising a U-shaped back frame and a U-shaped supporting frame arranged to nest one within the other, a cross rod pivotally connecting the free ends of said frames together, a second cross rod secured to said back frame and positioned inwardly of the closed end thereof, a sheet of flexible material disposed across said back frame and having longitudinally disposed and transversely disposed pockets receiving the back frame sides and the cross rods, and a flexible seat portion forming an extension of said sheet and supported from said second cross rod.

In testimony whereof, we have hereunto set our hands at Oakland, California, this 2nd day of August, 1928.

JEAN S. PONTEN.
OLAF W. PONTEN.
